UNITED STATES PATENT OFFICE

2,626,730

CONTAINER FOR PASTY SUBSTANCES

Josef Gabler, Zurich, Switzerland

Application August 15, 1946, Serial No. 690,779
In Switzerland February 15, 1944Section 1, Public Law 690, August 8, 1946
Patent expires February 15, 1964

5 Claims. (Cl. 222—326)

1

The present invention relates to a container for pasty substances, the container being fitted with a piston for extruding the container contents and also with means for changing the position of the piston in the container.

According to the invention the container is provided with an interchangeable inner container which serves to hold the pasty substances, and within which the piston, with unbroken surface on the side next the pasty substance, is detachably arranged, the means for displacing the piston being operative from the outer container and remaining at least partly attached to the outer container when the inner container is being changed.

Other and additional features and objects will be more fully disclosed in the following detailed description of this invention, when read in conjunction with the accompanying drawings, in which:

Fig. 1 shows a vertical section through a container according to a first form of arrangement,

Fig. 2 the lower end of the container shown in Fig. 1 with the parts in another position,

Fig. 3 a detail from Fig. 1 in side view,

Fig. 4 the piston for the container shown in Fig. 1, on a smaller scale,

Fig. 5 a second arrangement in vertical section with parts broken away,

Fig. 6 the lower part of the container shown in Fig. 5 with the parts in another position,

Fig. 7 a detail from Fig. 5 in side view,

Fig. 8 a seventh form of arrangement in axial cross-section,

Fig. 9 the side view of a detail from Fig. 8,

Fig. 10 a cross-section on the line A—A of Fig. 11 of a further form of arrangement,

Fig. 11 a vertical section through the form of arrangement shown in Fig. 10,

Fig. 12 is a detail variant for Fig. 11.

Fig. 13 an axial section, partly in view, of a container in a further arrangement,

Fig. 14 the view of a box-like container, partly in section,

Fig. 15 detail variant of Fig. 14,

Fig. 16 vertical section through a further arrangement of a container,

Fig. 17 a piece of a container, partly in section, partly in view,

Fig. 18 a section through the lower part of a further form of arrangement of the container,

Figs. 19 and 20 axial cross-section through two examples and

Fig. 21 a diagrammatic view of a part of Fig. 19 on reduced scale.

2

The container illustrated in Figs. 1—4 is in the form of a box with an outer jacket 1, a hinged cover 2 and an inner mirror 3 in the latter. At the lower end of the container, the bottom 5 is 5 rotatably arranged on the jacket 1, by means of a ring nut 4. A stirrup 6 is arranged so that it can swivel in a bearing 7 on the bottom 5. The jacket 1 has within it an interchangeable inner container 8, in which the pasty substance is contained. The inner wall of the container 8 is provided with a screw thread 9 in which a piston 10 screws, sealing tightly. The inner container 8 has an upper closing wall 11 with a depression 12 and an orifice 13 at the bottom of the depression 12. Two pins 14 on the container 8 fit into holes 15 of the jacket 1 and prevent the two parts 1, 8 from turning with respect to each other. On the lower side of the piston 10 two grooves 16, running parallel to each other, are 20 provided, into which fit pins 17 which are bent at an angle on the free ends of the arms of the U-shaped stirrup 6. A strut 18 keeps the arms of the stirrup at a certain distance apart. When the bottom 5 is turned with respect to the jacket 1, and consequently also with respect to the container 8, the stirrup 6 serves as operating means for the piston 10, so that it is displaced axially by the screw thread 9. In this way the stirrup 6 changes from its initial position shown in Fig. 2 into the position shown in Fig. 1 and the pasty substance contained in the inner container 8 is extruded through the orifice 13 during this movement of the piston. After the inner container 8 has been completely emptied, the bottom 5 is unscrewed from the jacket 1, the empty inner container 8 is removed and replaced by a new full container 8.

The arrangement shown in Figs. 5 to 7 differs from that described above, besides in other features, by the stirrup 6 having a telescopic withdrawable part 6'' in addition to the part 6'.

On the part 6'', besides the strut 18, a cross bar 19 is provided whose ends 17 form pins which fit into the grooves 16 of the piston 10. This telescopic form of the stirrup makes it possible to use a higher jacket 1 and a higher inner container 8 than in the first arrangement. In addition to that, the rotatable bottom 5' is detachably held on the wall of the container 1 by means of an expanding ring 20.

The variant illustrated in Figs. 8 and 8 is intended for high containers and a longer piston stroke. The inner wall of the container 8' and also the periphery of the piston 10' have in this case no screw thread, but are smooth. The links

of a toggle lever 36 in the form of a lazy-tongs are attached at one end to bearing 32 on the piston 10' while each of the other ends is pivotally connected to a moving nut 33. The nuts 33 run on left and right-hand threads 34 on a spindle with operating knob 35 carried rotatably in the bottom of the container.

According to the arrangement shown in Figs. 10-12 a member consisting of two co-axial spiral springs 37, coiled in opposite directions to each other, in the sense that the springs are coiled respectively in clockwise and counterclockwise direction, the coil expanding from each end adjacent the bottom piece 5, to each end terminating adjacent the piston. Each spring serves as an operating member for the piston 10 when the bottom piece 5 is rotated. One end of each of these springs 37 is fixed in a recess in the bottom piece 5, whilst the other ends engage by means of pins 38 into holes on the bottom of the piston 10. The cover 2 is hinged to a ring 39, which is fitted with lugs 40 as shown in Fig. 11, by means of which the ring 39 is detachably held in a groove 41 in the container 1. According to the variant shown in Fig. 12 the ring 39 is connected by means of a thread 42 to the container 1. The embodiments of the invention illustrated in Figures 10-12 are also provided with pins 14 and holes 15 as in the embodiments illustrated in Figures 1-4, to prevent relative rotation of the inner and outer containers.

Instead of the spiral springs 37 a leaf spring folded like a bellows could be provided.

The container shown in Fig. 13 has a casing 130 with a cover 131 arranged rotatably and detachably on it in a manner not shown in the drawing. Within the container, a cylindrical jacket 134, provided on the lower end with a set of teeth 133, is rotatably arranged, being turned by the cover 131 on which a pin 135 projects into a cut 136 in the cylinder jacket 134. At the lower end of the casing 130 a shaft 138 running at right angles to the axis of the container, is rotatably supported in a ring 137, the shaft carrying a toothed wheel 139 which engages with the set of teeth 133. On the shaft 138 is fitted a roller 140 on which is wound a pulling means 141.

The container 130 serves to hold a tube-like inner container 142, which contains the pasty substance to be extruded and is open at the back. In the container 142, a piston 143 can be displaced by means of a plate 144 in order to expel the substance, the free end of the pulling member 141 being attached to the lower side of the said plate. Between this plate and the bottom of the casing a compressed spring 145 is arranged. The lower end of this spring rests on a plate 146, which in its turn is passed through by the shaft 138 and lies with an edge part 148 on a roughened part 147 of the roller 140.

When the cover 131 is rotated, the cylinder jacket 134, and thereby the shaft 138 and the roller 140 are rotated by the toothed wheel 139. In this way the pulling member 141 is rolled on to or off the roller according to the direction of rotation, and the spring 145 is compressed or released. Because of the contact between the edge part 147 and the roughened part 148 of the roller 140, the latter is secured against unintentional rotation.

In the form of arrangement shown in Fig. 14 the casing has the form of a small box with hinged cover 149 and inner mirror 150. For turning the shaft 138 with the toothed wheel 139 and the roller 140, the rotatable bottom 151 of

the casing is here used, this being fitted with a set of teeth 152. The method of working of the device is similar to that described with reference to Fig. 13. In this form of arrangement and also in that shown in Fig. 13, the roller 140 can be provided with a self-locking wormwheel drive in order to prevent unintentional rotation. Then the toothed wheel 139 mounted on an intermediate shaft engages with the set of teeth on the bottom end of the jacket 134 or in the bottom of the casing 151, whilst a worm arranged on this intermediate shaft is in engagement with a wormwheel on the shaft 138.

In the arrangement shown in Fig. 15 the casing bottom 151 is again rotatable on the casing wall 131. The casing bottom carries in the middle a bobbin in the form of a disc-shaped raised part 153. The pulling member 141 enters the middle of the bobbin and leaves it through a lateral passage. One end of the pulling member is again attached to a plate 144 (Figs. 13 and 14), whilst the other end is fixed in the bore 154 of the casing wall 131. When the casing bottom 151 is rotated, the pulling member here is wound on to or off the periphery of the disc-like raised piece 153. Rollers could be provided at the spot in the disc-like raised piece where the pulling member turns at an angle, in order to reduce friction.

As shown in Fig. 16 the jacket 134 carries a ring 155 with an internal thread. Into this internal thread are screwed about one and a half turns of the coiled spring 145, arranged between the casing bottom and the plate 144. When the ring 155 is rotated in a suitable direction, coils of this spring are freed above the ring, so that they press on the plate 144 and a part of the contents of the container 142 are pressed out by the piston. Underneath the ring 155 the spring coils are pressed together, so that they cannot expand and have no effect on the spring pressure.

In Fig. 17, instead of the ring 155 (Fig. 16), a disc 156 is provided, with edge bent downwards and in contact with the wall of the cylindrical jacket 142, which is rotatable in the casing 130. The disc 156 has a central opening and to its edge a tubular-shaped part 157 is fixed, which serves as a guide for the spring, a part of a coil of the spring being held in this guide 157. When the disc 156 is rotated, the spring is displaced within this tube-shaped guide 157, whereby coils of the spring subject to pressure under the disc, i. e. between the bottom of the casing and the disc, are made free. Above the disc the coils of the spring are free to expand and exert their pressure on the piston and the pasty substance introduced into the casing.

The arrangement shown in Fig. 18 serves for pressing out tubes with collapsible walls which can be pressed together. This arrangement has a plate 143 which, with an external thread, is in screw-thread engagement with an inner thread of the rotatable cylinder jacket 142. Between the plate 143 and the bottom of the casing the compressed spring 145 is arranged. Any suitable means, for example, the pin 14 and hole 15 illustrated in Figure 1, or its equivalent, a lug 190 and groove 181, illustrated in Figure 18, may be employed for causing the jacket 142 to rotate as a unit with the outer container. When the jacket 142 is rotated, the plate 143, which is prevented from rotating by the spring 145, screws upwards along the internal thread of the jacket 142 and exerts a pressure on the tube present in the casing 130 above the plate.

Instead of the tube-like guide 157 as shown

in Fig. 17, only an eccentric opening for the passage of the coiled spring could be provided in the disc 156.

If the container to be pressed out by means of the device is the usual commercial form of tube, the plate resting on the spring may be provided with a straight or arc-shaped slot into which the usual straight or arc-shaped, bent, flat-pressed end of the tube can be pushed.

Under certain circumstances, instead of using the screw thread to retard the motion of the plate in the casing, so that the action of the spring comes into effect only as desired, the friction between the rotatable cylinder jacket and the periphery of the plate may be so chosen that displacement under the influence of the spring pressure occurs only when turning of the cylinder jacket takes place.

Under certain circumstances it may be preferable to connect to the plate the bottom of the container which has to be pressed out. For this purpose special fixing members may be provided, or the plate may be fitted with a suction bowl to which the bottom of the container adheres. Also a permanent magnet could be fixed to the plate, and an armature working in connection with it could be fixed to the bottom of the container.

The container illustrated in Fig. 19 is in the form of a box with the outer jacket 1 carrying a detachable ring 158 bearing the hinged cover 2. The ring 158 is closed by a wall 159 with a central opening 160 and a hub 161. On the hub 161 and between the wall 159 and another wall 162 formed in the ring 158, a ratchet wheel 55 is journaled. A push button 56 is secured to an arcuate piece 163 bearing a tooth 164 cooperating with the ratchet wheel 55 as may be seen in Figure 40. The piece 163 is secured to one end of a spirally wound spring 165 the other end of which is held on the ring 158. A hook 166 on the piece 163 engages a hook 167 on the hinged cover 2 and holds it in its closed position as long as the push button 56 is not depressed. On depression of the push button the cover 2 is released and on each further depression of the push button the ratchet wheel 55 is rotated by the cooperation of the tooth 164 with this wheel.

The jacket 1 encloses an interchangeable inner container 8 filled with the pasty substance. The inner wall of the container 8 is provided with a screw thread 9 in which a piston 10 screws. Two pins 14 on the container 8 engage two openings arranged in a plate 168 secured to the ratchet wheel 55.

A helical spring 169 arranged between the bottom of the jacket 1 and the piston 10 tends to lift the latter. A plate 170 located between the upper end of the spring 169 and a boss 171 of square section positioned on the underside of the piston engages a depression 172 in this plate 170 preventing rotation of the piston upon rotation of the container 8 by the press button and the ratchet wheel.

In the arrangement of Fig. 20 the outer box 173 possesses a cover 174 with a central bore 175 through which passes the pasty substance contained in an interchangeable inner container 176.

In the cover 174 is forced elastically the upper end of a cylindrical wall 178 rotatably arranged in the box 173 and bearing the bottom 177 also rotatable in the box. Two brackets 179 of different height are secured to this bottom 177. A helical spring 180 lies between a rotatable disc 181 on the bottom 177 and a plate 182. Plate 182

and a piston 183 displaceable along the inner wall of the container 176 are connected by a threaded center piece 184 on the piston and a threaded recess 185 on plate 182.

By rotating the cover 174 the wall 178 and thereby the bottom 177 are also rotated. By the brackets 179 turns of the spring 180 which does not rotate are freed so that they press on the plate 182. This force is transmitted to the piston 183 which is set in movement and presses a part of the content of the container out through the bore 175.

The elasticity of the spring causes this movement to continue after the rotation of the cover 174 has ceased.

In this way the amount of pasty substance pressed through the bore 175 may be greater as desired. By rotating the cover 174 backwards the pressure of the spring on the plate 182 is released and simultaneously the threaded piece 184 and the recess 185 are disconnected so that no pressure remains on the piston 183 causing the pasty substance to flow out. The friction between the piston and the wall of the container is so chosen as to prevent rotation of the piston.

What I claim as new, and desire to secure by Letters Patent, is:

1. A dispensing container for pasty substances comprising a substantially cylindrical outer container having an upper portion and a bottom portion rotatably attached to the upper portion, an inner container within the outer container containing the substance to be dispensed and adapted to rotate integrally with the upper portion of the outer container, said inner container having screw threads on the inner surface of the walls thereof, a piston in the inner container having screw threads on the outer periphery thereof adapted to engage the threads on the inner container, a helical spring engaging at one end the bottom portion of the outer container and at the other end the piston whereby on relative rotation of the upper and bottom portions of the outer container the piston is moved longitudinally in the inner container.

2. A dispensing container for pasty substances comprising a substantially cylindrical outer container, a base closing one end of the outer container rotatably attached thereto, an inner container within the outer container containing the substance to be dispensed and adapted to rotate therewith, screw threads on the inner surface of the inner container, a piston within the inner container, the piston having screw threads on the outer periphery thereof adapted to engage the threads on the inner surface of the inner container, and a helical spring between the piston and the base, said spring engaging the piston at one end and the base at the other end, whereby rotation of the base relative to the outer container moves the piston longitudinally in the inner container.

3. A dispensing container for pasty substances comprising a substantially cylindrical outer container, a base closing one end of the outer container rotatably attached thereto, an inner container within the outer container containing the substance to be dispensed and adapted to rotate therewith, said inner container slidably engaging and supported by the outer container, screw threads on the inner surface of the inner container, a piston within the inner container, the piston having screw threads on the outer periphery thereof adapted to engage the threads on the inner surface of the inner container, and a

helical spring between the piston and the base, said spring engaging the piston at one end and the base at the other end whereby rotation of the base relative to the outer container moves the piston longitudinally in the inner container.

4. A dispensing container for pasty substances comprising a substantially cylindrical outer container, a base closing one end of the outer container rotatably attached thereto, an inner container for the substance to be dispensed interchangeably secured within the outer container and adapted to rotate therewith, screw threads on the inner surface of inner container, a piston within the inner container, the piston having screw threads on the outer periphery thereof adapted to engage the threads on the inner surface of the inner container, said piston having an irregular surface facing the base member, and a compressed helical spring between the piston and the base member, said spring adapted to engage the irregularities in the surface of the piston and the base member whereby relative rotation between the piston, spring and base member is prevented and rotation of the base relative to the outer container moves the piston longitudinally in the inner container.

5. A dispensing container for pasty substances comprising a substantially cylindrical outer container, a base closing one end of the outer container rotatably attached thereto, an inner container for the substance to be dispensed interchangeably secured within the outer container and adapted to rotate therewith, screw threads on the inner surface of inner container, a piston

within the inner container, the piston having screw threads on the outer periphery thereof adapted to engage the threads on the inner surface of the inner container, said piston having recesses in the surface facing the base member, and a compressed helical spring between the piston and the base member, said spring adapted to engage the recesses in the surface of the piston and the base member whereby relative rotation between the piston, spring and base member is prevented and rotation of the base relative to the outer container moves the piston longitudinally in the inner container.
